COMBINED IRONING BOARD AND IRON SUPPORT

Walter M. Schwartz, Philadelphia, Pa., assignor
to Proctor & Schwartz, Inc., Philadelphia, Pa.,
a corporation of Pennsylvania

Application March 10, 1939, Serial No. 261,072

3 Claims. (Cl. 38—107)

This invention relates to a combined ironing board and means for supporting an iron adjacent to the board, and has for a particular object thereof the provision of a construction of this character in which the iron support is accessible from any position along the board and, at the same time, will not materially interfere with the passage of garments over the board.

A more specific object of the invention is the provision of an iron support which, while extended from a point adjacent the body or larger end of the ironing board to a point at which the narrowing of the board begins, is supported only at the butt end of the board and has its free portions spaced from the adjacent edge of the board a distance such that clothing may be placed about the board for ironing purposes.

Another object of the invention is the production of a device of this character which is so arranged that the iron may be readily slid from the board to the support and which is further equipped with means preventing accidental displacement of the iron over what is the far edge of the support with respect to the board proper.

A further object of the invention is to produce a device of this character which may be detachably connected to the board.

These and other objects I attain by the construction shown in the accompanying drawings wherein, for the purpose of illustration, I have shown a preferred embodiment of my invention and wherein:

Fig. 1 is a plan view of an ironing board constructed in accordance with my invention;

Fig. 2 is an end elevation thereof showing the iron support in its operative position;

Fig. 3 is a view similar to that of Fig. 2 but showing the iron support in the process of removal or installation;

Fig. 4 is a perspective view of a bracket attached to the ironing board; and

Fig. 5 is a perspective view showing the co-acting brackets attached to the iron support.

Referring now more particularly to the drawings, the numeral 10 generally designates an ironing board which may be of any usual or ordinary construction. The numeral 11 generally designates an iron support which, in its operative position, has its upper surface coplanar with the upper surface of the ironing board, as more clearly shown in Fig. 2. The iron support is equipped with a covering 12 of heat insulating material and has a body portion 13 formed of sheet metal and defined at its outer edge, or that edge most remote from the ironing board, by an upstanding

flange 14. The inner edge of the support is preferably flanged downwardly, as indicated at 15, this flanging being continued about the outer end edge 11a of the board for at least a portion of its width so that a smooth surface is presented to prevent accidental damage to clothing passed over the board 10. The iron support is supported from the ironing board by means designated generally at 16 and disposed adjacent the butt or larger end of the ironing board, this means supporting the iron support with its inner edge in spaced relation to the adjacent edge of the ironing board, thus affording a slot or gap 17 therebetween through which clothing may be passed for disposition upon the surface of the board.

The supporting bracket may be of any suitable construction. As at present illustrated, it comprises a member 18 secured to the board adjacent the butt end thereof and at its under surface, and a compound bracket comprising a pair of arms 19 secured to the iron support adjacent the end thereof and notched at 20 for the reception of the inner flanged edge of the iron support. The spaced arms 19 are adapted to engage the under surface of the board at opposite sides of bracket 18. The bracket 18 includes spaced upstanding lugs 21 arranged adjacent its end edges and upstanding adjacent the side of the ironing board. These lugs have their upper surfaces notched at 22 to rotatably receive pivot means carried by the arms 19 of the compound bracket attached to the ironing board. While this pivot means may comprise pins carried by the arms, I preferably employ a bar connecting the arms as shown. When this bar is placed in the notches 21 with the support in the position shown in Fig. 3, the support may be rotated to move it to the position illustrated in Fig. 2 in which it is ready for use.

It will be obvious that, with the iron support in the position shown in Figures 1 and 2, the iron may be readily slid from the board to the support without lifting the same and, since the flange 14 will serve to limit the movement of the iron, this may be accomplished by simply giving the same an impulse sufficient to cause the same to be moved onto the support. To insure against tipping of the iron, the space 17 should be less than one-half the width of the iron.

Since the means of attachment illustrated is but one of many forms which may be adopted to mount the iron support upon the board, I do not wish to be understood as limiting myself to the

arrangement herein disclosed except as herein-after claimed.

I claim:

- 6 1. In combination with an ironing board having a butt portion having a substantially straight rear edge and a working surface, an elongated iron support extending along said edge and having its upper surface substantially coplanar with said working surface and its inner edge in spaced 10 substantially parallel relation to said edge of the ironing board and a supporting connection between the board and the rear end of the iron support disposed adjacent the free end of the butt portion of the board.
- 15 2. In combination with an ironing board having a butt portion having a substantially straight rear edge and a working surface, an elongated iron support extending along said edge and having its upper surface substantially coplanar with 20 said working surface and its inner edge in spaced substantially parallel relation to said edge of the ironing board and a supporting connection between the board and the rear end of the iron support disposed adjacent the free end of the butt 25 portion of the board, said connection comprising bracket means on said iron support including longitudinally-spaced transversely-disposed arms

the inner portions of which are adapted to engage beneath the board, a bar connecting said arms, and bracket means on said board including members disposed adjacent said arms and notched in their upper surfaces to engage said bar.

- 5 3. In combination with an ironing board having a butt portion having a substantially straight rear edge and a working surface, an elongated iron support extending along said edge 10 and having its upper surface substantially coplanar with said working surface and its inner edge in spaced substantially parallel relation to said edge of the ironing board and a supporting connection between the board and the rear end 15 of the iron support disposed adjacent the free end of the butt portion of the board, said connection comprising bracket means on said iron support including longitudinally-spaced transversely-disposed arms the inner portions of which are adapted to engage beneath the board, bracket means on said board including members disposed adjacent said arms and notched in their upper surfaces, and pivot means projecting from the arms and adapted to engage in the notches of 20 the members.

WALTER M. SCHWARTZ.
